UNITED STATES PATENT OFFICE.

WALTER E. BANGS, OF WORCESTER, MASSACHUSETTS.

VACUUM CARPET-CLEANER.

1,168,272.

Specification of Letters Patent. Patented Jan. 18, 1916.

Application filed April 7, 1913. Serial No. 759,368.

To all whom it may concern:

Be it known that I, WALTER E. BANGS, a citizen of the United States, residing at Worcester, in the county of Worcester and 5 Commonwealth of Massachusetts, have invented a new and useful Improvement in Vacuum Carpet-Cleaners, of which the following, together with the accompanying drawing, is a specification.

10 My invention relates to vacuum carpet cleaners and more particularly to that class of carpet cleaners which include both a brush and a vacuum nozzle so arranged as to coöperate in cleaning surfaces of a carpet or 15 rug, or any similar surface over which the cleaner may be moved.

One object of the invention is to provide an improved form of combination vacuum and brush carpet cleaner in which the relative 20 positions of the brush and the vacuum nozzle and the position of each with relation to the surface to be cleaned may be adjusted in order to adapt the cleaner to the particular character of any surface to be cleaned, 25 or of the matter which it is desired to remove from such surface.

Another object of the invention is to provide a cleaner of the type already referred to which may be used not only for cleaning 30 carpets, rugs, and other floor surfaces, but which may be also conveniently used for cleaning walls, portières, and various other objects not easily cleaned with the ordinary form of combined brush and vacuum 35 cleaner.

Other objects and advantages will appear from the following description taken in connection with the accompanying drawing, in which—

40 Figure 1 is a plan view of one embodiment of my invention, certain interior details being shown in broken lines. Fig. 2 is an end view of the forward portion of the machine shown in Fig. 1, the supporting 45 wheel being removed. Fig. 3 is a view similar to that shown in Fig. 2, but showing a different adjustment of the parts. Fig. 4 is a detail view of a plate used in the construction of the machine. Fig. 5 is an end 50 view similar to that shown in Figs. 2 and 3, but with certain parts shown in those figures removed to show further details. Fig. 6 is a detail view of one of the brush supporting arms shown in Figs. 2 and 3.

55 Like reference characters refer to similar parts in the different figures.

In the form of invention shown in the drawing, the hollow box or casing 1 is removably secured by the thumb screws 2 to the forward end of any suitable box 3, the 60 box 3 containing the bellows for producing the vacuum, and also containing a suitable receptacle for the dust and other matter picked up by the cleaner. Inasmuch as the box 3 and the bellows and dirt receptacle 65 contained therein, form no part of the present invention, no description thereof is deemed necessary, and any well known form may be used so long as it may be attached at its forward end to the box 1. A plate 4 70 lies against each end of the box 1 so as to close the opening 5 in the end of the box, each of the plates having an opening 6 which is passed over a pivot 7 so that the plate may rotate about this pivot in a manner and for a purpose to be described. The extent of movement of each plate about its pivot 7 is limited by a pin 8 carried by the box 1, the pin passing through a slot 9 in the plate and carrying a milled nut 10 to 80 secure the plate in any adjusted position. Each plate 4 carries a pivot 11 secured in the opening 12 in the plate, and mounted upon the pivot 11 is an arm 13 having a small shoulder 14 upon its upper edge. A 85 pin or stop 15 carried by the box 1 and extending through a slot 16 in the plate 4 is provided to engage the shoulder 14, as shown in Fig. 2, and limit the upward movement of the plate 4 about the pivot 7. The 90 free end of the arm 13 carries a pin 17 upon which turns the supporting wheel 18.

It is clear that if the plates 4 are rotated downwardly about their pivots 7, the pivots 11 carried by the plates 4 will be moved 95 forwardly so as to slide the upper edges of the arms 13 along the stops 15 into the position indicated in Fig. 3. The stops 15 thus act to force the free ends of the arms 13 downwardly so as to cause the lowest points in the peripheries of the supporting wheels 18 to project to a greater extent below the box 1, and as a result the box 1 will be lifted somewhat from the floor or other surface upon which the wheels 18 rest. The wheels 100 are then of course secured in this position by tightening the nuts 10.

Each of the plates 4 has a projection 19 at its forward edge, the free end of the projection extending beyond the front edge 110 of the box 1 and being bent inwardly at right angles to the plate. A bar 20 has each

of its ends formed with an opening therein to receive the inwardly bent free ends of the extensions 19, this bar 20 acting as a handle by means of which the positions of the 5 plates 4 may be adjusted. The bar 20 carries a pad 20^a along its front surface to prevent injury to furniture and other objects.

Each plate 4 carries a pivot 21 secured in the opening 22 in the plate. Upon each 10 pivot 21 is mounted an arm 23 having an opening 24 therein which acts as a bearing to support the axle 25 of the brush 26. A slightly elongated opening or slot 27 is provided in each of the plates 4 to permit 15 relative movement between the plates and the brush. Each end of the axle 25 carries a small friction wheel 28 which lies inside the rim of the supporting wheel 18. The inner surface of the rim of the supporting 20 wheel 18 is preferably composed of some suitable friction material 29, such as rubber, and the periphery of the friction wheel 28 is similarly composed of friction material 30. A small spring 31 secured at one end to the 25 plate 4 and at the other end to the free end of the arm 23 causes the friction wheel 28 to press firmly against the inner surface of the rim of the supporting wheel 18, so that the brush 26 may be driven by the supporting 30 wheels of the machine.

A trough shaped member 32 secured along the under face of the body portion of the box 1 is provided with a longitudinal opening under the brush so that the brush may 35 be lowered, as shown in Fig. 3, to come into contact with the carpet or other surface being cleaned. The brush is raised or lowered through this opening by rotating the plates 4 as has been described, downward movement 40 of the plates 4 about their pivots 7 carrying the pivots 21 with them so as to force the brush downwardly through the opening, the friction wheels 28 merely rolling along the inner frictional surfaces of the supporting 45 wheels 18. Rotation of the plates 4 in the reverse direction until the shoulders 14 engage the stops 15 causes the brush to rise through the longitudinal opening in the member 32, so that said member 32 may act principally 50 as a vacuum nozzle, the supporting wheels 18 being raised at the same time so as to allow the member 32 to lie close to the surface being cleaned, as shown in Fig. 2.

The proportions of the parts shown in the 55 drawing and which I now consider preferable are such that when the brush is raised, as shown in Figs. 2 and 5, the lowest part of the brush and the under surface of the nozzle 32 are each about $\frac{1}{16}$ " above the surface to be cleaned, and when the brush is lowered, as shown in Fig. 3, the brush will just touch the surface of the carpet, while the under surface of the nozzle 32 will be raised about $\frac{1}{16}$ " above the surface to be 60 cleaned.

The rear wall of the box 1 is provided with a suitable opening 33 which allows the bellows or other vacuum producing means to draw air and dirt through the longitudinal opening in the nozzle 32 and thence into the 70 dirt receptacle in the box 3.

In case it is desired to pick up dust and other light matter from the surface to be cleaned the parts may be adjusted as shown in Fig. 2. The weight of the machine with 75 the parts adjusted in this way will cause the supporting wheels 18 to sink slightly into the yielding surface of a rug or carpet, so that the nozzle 32 will lie very close to such surface or even in contact therewith, the machine acting merely as an ordinary vacuum cleaner, or in case the brush is not raised too far the brush may also assist somewhat by stirring up the matter to be picked up.

With the parts adjusted as shown in Fig. 85 3, the brush, as has been indicated, extends downwardly as far as the lowermost points of the supporting wheels 18, and inasmuch as these wheels will sink more or less into the carpet or rug, the brush will act effectively in sweeping up the particles to be 90 cleaned from the carpet or rug, the current of air produced by the bellows then acting to draw such particles through the nozzle 32 and into the dirt receptacle in the box 3. 95 This adjustment of the parts is most effective in picking up heavier particles, such as matches, and particles, such as threads, which adhere to the surface to be cleaned. When it is desired to clean portières, walls, 100 upholstered furniture, and like objects, the brush is not necessary and may be raised into the position indicated in Figs. 2 and 5, so that the cleaning may be accomplished by the vacuum alone. When the machine is to 105 be used in this manner the box 3 may be removed from the box 1 by loosening the thumb screws 2, and the usual vacuum hose from any suitable vacuum producing mechanism driven by an electric motor, or otherwise, may be attached to the rear wall of the 110 box 1 so as to draw air through the opening 33. The box 1 is comparatively light and portable so that its nozzle 32 may be easily passed over surfaces, such as referred to. 115

While I have herein shown and described details of one form of my invention, I do not wish to be limited to such details as it is obvious that certain changes may be made within the scope of the appended claims 120 without departing from the spirit of the invention, but

Having described my invention what I claim as new and desire to secure by Letters Patent is:

1. A carpet cleaner including a vacuum nozzle, a brush, a supporting wheel, and means for simultaneously raising or lowering the brush and the wheel with relation to the nozzle.

2. A carpet cleaner including a vacuum nozzle, a brush at the opening of the nozzle, a supporting wheel, and means for raising or lowering the wheel with relation to the nozzle and for simultaneously raising or lowering the brush to a greater extent. 50
3. A carpet cleaner including a casing, a brush, a supporting wheel having a friction surface, a driven wheel connected with the brush and having a friction surface, an arm carrying the driven wheel and one end of the brush, a plate pivoted to the casing and carrying the supporting wheel and the arm, and means for yieldingly pressing the arm about an axis to hold the friction surfaces of the supporting and driven wheels together, whereby the supporting wheel and the brush may be simultaneously raised or lowered by turning the pivoted plate about its pivot. 60
4. A carpet cleaner including a casing carrying a vacuum nozzle, a plate pivotally connected to the casing, an arm pivoted at one end to the plate, a supporting wheel carried by the free end of the arm, and a stop contacting with an edge of the arm, said edge of the arm being shouldered, whereby the stop forces the wheel downwardly as the plate is turned on its pivot. 70
5. A carpet cleaner including a casing carrying a vacuum nozzle, a plate pivotally connected to the casing, an arm pivoted at one end to the plate and having a shoulder, a supporting wheel carried by the free end of the arm, and a pin on the casing projecting above and resting upon the arm to engage the shoulder so as to limit rotation of the plate in one direction and to force the wheel downwardly as the plate is turned in the other direction. 80
6. A carpet cleaner including a vacuum nozzle, a plate, an arm pivoted at one end to the plate, a brush supported by the free end of the arm, a driven wheel connected with the brush, a driving wheel, and yielding means tending to turn the pivoted arm to cause the driven wheel to maintain contact with the driving wheel, the plate be- 90
- ing pivoted to allow the brush to be raised or lowered with relation to the nozzle. 50
7. A carpet cleaner including a casing carrying a vacuum nozzle, a plate pivotally carried by the casing, an arm pivoted to the plate, a supporting wheel carried by the free end of the arm, a stop contacting with an edge of the arm, said edge of the arm being shouldered, whereby the stop forces the arm and supporting wheel downwardly when the plate is turned on its pivot, a second arm pivoted to the plate, a brush supported by the free end of said second arm, whereby the brush is forced downwardly simultaneously with the supporting wheel when the plate is turned on its pivot, a driven wheel connected to the brush, and yielding means for pressing the driven wheel against the supporting wheel. 65
8. A carpet cleaner including a casing carrying a vacuum nozzle, a plate, a notched arm pivoted to the plate, a supporting wheel carried by the free end of said arm, a pin on the casing projecting above and resting upon the arm, a second arm pivoted to the plate, a brush supported by the free end of said second arm, a driven wheel connected to the brush, and yielding means acting on said second arm to cause the driven wheel to press against the supporting wheel so as to be driven thereby, the plate being adjustable about a pivot to allow the brush and supporting wheel to be simultaneously raised or lowered. 75
9. A carpet cleaner including a casing carrying a vacuum nozzle, a pair of plates pivotally carried by the casing, an arm pivoted to each plate, supporting wheels carried by the free ends of the arms, and means contacting with the arms to force them downwardly as the plates are turned about their pivots, whereby the wheels are depressed with relation to the nozzle. 85
